UNITED STATES PATENT OFFICE

122,855

DESIGN FOR AN AIRPLANE

Jean A. Roché, Dayton, Ohio

Application November 2, 1938, Serial No. 80,836

Term of patent 7 years

To all whom it may concern:

Be it known that I, Jean A. Roché, a citizen of the United States, residing at Dayton, in the county of Montgomery and State of Ohio, have invented a new, original, and ornamental Design for an Airplane, of which the following is a specification, reference being had to the accompanying drawings, forming part thereof, wherein:

Fig. 1 is a top plan view of an airplane showing my new design;

Fig. 2 is a front elevational view of the said airplane design; and

Fig. 3 is a side elevational view of said airplane design with the landing gear retracted as in flight.

Figure 4 is a top perspective view of said airplane design in an enlarged scale.

The dominant features of my new design reside in the association of the cabin, wings and motor nacelles, as shown.

I claim:

The ornamental design for an airplane, as shown and described.

JEAN A. ROCHE.
